UNITED STATES PATENT OFFICE.

KELLY M. TURNER, OF NEW YORK, N. Y.

ATTACHMENT FOR ACOUSTICONS PERMITTING USE OF ORDINARY TELEPHONES.

No. 839,050.

Specification of Letters Patent.

Patented Dec. 18, 1906.

Application filed April 9, 1906. Serial No. 310,617.

To all whom it may concern:

Be it known that I, KELLY M. TURNER, a citizen of the United States, residing at New York city, in the borough of Manhattan and

5 State of New York, have invented certain new and useful Improvements in Attachments for Acousticons Permitting Use of Ordinary Telephones, of which the following is a full, clear, and exact description.

10 My invention relates to a telephonic attachment by means of which deaf persons are not only able to hear ordinary conversation, but may converse over the telephone as well.

15 The invention has particular reference to use with the acousticon, an instrument which employs a special form of transmitter adapted to be carried in the vest or coat pocket and which multiplies the sound directed against it, so that a deaf person may 20 understand the same. For this purpose said transmitter is connected in a telephone-circuit with a receiver, which the person places against his ear when he wishes to converse. These articles are sold upon the market and 25 are carried by deaf persons for constant use.

25 The aim of my present invention is to provide an additional attachment by which the above outfit is made adaptable to receive conversation and sounds over the usual telephones.

30 With these and other objects in view my invention consists in the construction, combination, in the location, and in the arrangement of parts, as hereinafter set forth and 35 shown and finally particularly pointed out in the appended claims.

35 In the drawings, Figure 1 illustrates the manner of use of an outfit embodying my invention. Fig. 2 is a front view of my attachment. Fig. 3 is a side view of the attachment, showing the same in position to be applied to the acousticon-transmitter. Fig. 4 shows the device in its operative relation to a telephone-receiver.

40 Deaf persons are ordinarily more seriously inconvenienced by their inability to receive telephone messages than by any other relation. This is by reason of the fact that the loudness of telephone transmission cannot be 45 increased on the ordinary instruments without setting up violent vibrations of the telephonic diaphragms, which destroy the purity of the sound. By my present invention I provide means by which the sound delivered 50 from an ordinary telephone-receiver is retransmitted into a form of transmitter

adapted to multiply the sound and from which it can be readily heard in a special local circuit provided by the acousticon apparatus.

60

Referring to the drawings and to the various views and reference-signs thereof, in which like parts are designated by the same reference-sign wherever they occur, A indicates an ordinary desk-telephone outfit comprising a transmitter A' and a receiver A².

65 B indicates an acousticon outfit, including an acousticon-transmitter B' and an acousticon-receiver B². The usual form of the acousticon-transmitter is illustrated in Fig. 3, it being commonly provided with a hook or clasp b, by which it is secured to the vest or coat pocket in use.

70 In its preferred form my invention includes a ring or annular casing 1, having a straight cylindrical portion 2 and an end face 3, centrally perforated with a hole 4 of sufficient diameter to receive the end of the ordinary telephone-receiver A², as shown in Fig. 4. The straight cylindrical portion or rim 75 terminates in a circular edge 5, which lies in a flat surface or plane, so as to be capable of closely engaging the face of the acousticon-transmitter B'.

80 85 85 indicates spring-prongs secured around the rim 2 and which engage over the sides of the acousticon-transmitter B', so as to hold the two members closely together.

85 The use and operation are as follows: Normally a deaf person will be provided with the 90 acousticon outfit, and will proceed with his regular vocations and pursuits with the acousticon-transmitter B' hooked upon the pocket of the vest or coat or otherwise conveniently disposed to receive the conversation. When the deaf person goes to a telephone, the device embodying the present invention is placed upon the acousticon-transmitter, where it is held by the prongs 6. It is then merely necessary to press the usual 100 telephone-receiver into the opening 4 of the ring or casing 1, whereby a chamber is produced into which the sounds from the receiver are gathered and confined. All the sound of the telephone-receiver is therefore 105 impelled into the acousticon-transmitter B', and by which it is multiplied and retransmitted, so as to be received by the deaf person in the usual way.

110 What I claim is—

1. An attachment for use with the acousticon comprising a ring or annular casing

formed to fit closely upon the face of an acousticon-transmitter, and having a hole or perforation to receive the usual receiver of a telephone outfit.

5. 2. An attachment for use with the acousticon, comprising a casing having a straight cylindrical portion or rim and an end wall or face having a hole or perforation therein, said perforation being adapted to receive the usual receiver of a telephone outfit, and means upon said rim for securing the casing to an acousticon-transmitter.

3. An attachment for use with the acousticon, comprising a casing having a straight cylindrical portion or rim, a front wall or face with a hole or perforation therein, and prongs upon said rim by which it is secured to an acousticon-transmitter. ¹⁵

In witness whereof I subscribe my signature in the presence of two witnesses.

KELLY M. TURNER.
